COMBINED CUP TRAY AND ASH RECEIVER

Benjamin Pitts, 9929 Chenlot, Detroit, Mich. 48204

Filed Mar. 7, 1972, Ser. No. 232,657

Term of patent 14 years

Int. Cl. D27—03
U.S. Cl. D85—2 K

FIG. 1 is a perspective view of a combined cup tray and ash receiver showing my new design;

FIG. 2 is a bottom plan view;

FIG. 3 is a top plan view of a combined cup tray and ash receiver showing a modified form of my new design; and

FIG. 4 is a left side elevational view thereof.

I claim:

The ornamental design for a combined cup tray and ash receiver, as shown and described.
